UNITED STATES PATENT OFFICE.

GEORGE WESTINGHOUSE, JR., OF PITTSBURG, PENNSYLVANIA.

ELECTRIC FLUID-PRESSURE ENGINE.

SPECIFICATION forming part of Letters Patent No. 352,520, dated March 1, 1887.

Application filed August 30, 1886. Serial No. 212,773. (No model.)

To all whom it may concern:

Be it known that I, GEORGE WESTINGHOUSE, Jr., residing at Pittsburg, in the county of Allegheny and State of Pennsylvania, a citizen of the United States, have invented or discovered certain new and useful Improvements in Electric Fluid-Pressure Engines, of which improvements the following is a specification.

10 In the accompanying drawings, which make part of this specification, Figure 1, Sheet 1, shows a sectional view of the main operative parts of my improved engine. Fig. 2, Sheet 2, illustrates, by diagram of a railway track, switch, and signals, one of the many uses to which my improvement may be applied. Fig. 3 shows one form of signal and post adapted for use in the signal system of Fig. 2, and Fig. 4 illustrates the manner of using such engines in 20 series.

For many purposes in the arts it is important to be able to apply a motive power at a distance from the operator's stand or position, and also at two or more distant points, and 25 also to cut off, reverse, and reapply such power, sometimes with great frequency and rapidity as well as certainty. This is especially true in the construction and operation of railway switches, signals, gates, &c., and while 30 my present invention is particularly applicable to the purposes or uses thus indicated, it may also be applied generally to producing and reversing motion at a greater or less distance, especially where the range of motion is 35 comparatively short and the demand for it is intermittent or irregular. As a motive power I employ fluid under pressure, either gaseous or liquid, and lead the same by suitable conduits from the place of storage or compression, 40 or from the accumulator of either head, to the point or points where its use or application is desired, or in convenient proximity thereto. I there utilize it, by means of a suitable engine, as a cylinder and piston at each such point or 45 place. In such apparatus a valve is required in order to supply and exhaust the fluid-pressure. Now, in my present invention, I provide for moving or actuating this valve by the same fluid-pressure which actuates the engine; and to this end I add a piston, subject 50 to fluid-pressure in opposite directions, and

by the use of electrically-actuated escape-valves alternately opening, so as to vary the pressure operative on the piston, I provide for moving such piston, and with it the main cylinder-valve, in either direction. I thus utilize the short range of motion of an armature in securing the shifting of a main distributing-valve, the motion of which is longer, and, in fact, is too long to be advantageously and economically worked directly by an electro-magnet. The use of an electro-magnet in this manner gives me an easily-worked, effective, and convenient means of applying a motive power at a greater or less distance, or at a point or points not conveniently accessible, or at several points from a single stand.

A, Fig. 1, represents an engine-cylinder suitable for use with compressed air or other pneumatic or hydraulic power, and A' is a piston thereof, and A'' is the piston-stem. A distributing-valve, V, of any suitable construction, is employed, such as will supply and exhaust the fluid-pressure through a suitable arrangement of supply and exhaust ports, a and a'. The valve-chest B contains a double-ended piston, the heads b and b' of which are connected by a hollow stem, c, and a recessed block or U-shaped fork, V, on or connected with such stem engages the valve V in such manner as to give it the proper motion. Fluid-pressure enters the chest B by a branch, m', from the main conduit m, Fig. 2, entering a port, as indicated by dotted lines at b', Fig. 1, and a small port, c', in the side of the stem c provides for keeping up the same pressure inside the hollow of the stem as outside. The piston-heads b and b' are packed in any suitable way so that leakage past them shall be small, or they may be tightly packed and a small or shallow groove (indicated by the heavy black lines o) may be provided for a slight leakage of fluid-pressure past them, or a very small hole may be made through each of such heads, so that fluid-pressure may be admitted to the other sides or ends of such heads in sufficient amount to move them either way when the pressure in the opposite end is relieved.

In the axial line of the hollow stem c in the heads or ends of the chest B, I bore a pair of valve-chambers, in which I arrange the valves s, which seat outwardly with the pressure,

and a pair of ports, $s' s'$, open from outside or beneath the seats to the open air, so that such valve-chambers, seat-openings, (when the valves are unseated,) and the ports s' constitute 5 escape-ports. Inside the hollow stem c are the rods $c' c'$, which at their outer ends abut against the tops of the valves $s s$, and springs c^1 and c^2 are arranged between the end colars and the bottoms of recessed seats in the ends of the piston-heads; but these springs are preferably of 10 such length and so arranged that they do not act in seating each its valve until near the end of the piston-stroke. The seating of these valves is their chief and only essential function, 15 though in this work they are aided by fluid-pressure acting, through the port c' , on the adjacent ends of the rods $c' c'$.

Beneath the valves (that is, on the ends toward which they seat) are the unseating 20 thrust-rods $e e$, each abutting against a screw-stem, e^1 , connected to a cap, D' , which constitutes the armature of a helix or coil, D , and which latter is inclosed within the hollow annular core-extension D^2 . This gives me what 25 is in effect an electro-magnet at each end of the chest B , and I only prefer the form or construction shown because it gives me in compact form and well inclosed a helix of considerable power through a short range of motion, 30 but long enough to unseat or open the valves. The thrust-rods e and their surrounding guides 35 may be made of brass, or otherwise constructed so as not to be affected in their action by the tubular core D^2 , which, if used, gives to that extent a solenoid construction and action. Over the ends are the covers D^1 .

In order the better to explain the operation of this engine, I will suppose it to be incorporated into a railway switch and signal apparatus, as illustrated in Fig. 2. Here the piston-stem A^2 is connected with any desired form of switch-shifting mechanism, such that as the piston moves one way or the other it may, through switch-bridle q , shift the movable rails q' one way or the other. A battery, y , or other source of electric power, may be arranged at any convenient point for the operator, as in a cabin, C , and a make-and-break mechanism or key may be added, as at y' , so 45 that either of two wires, 1 2, may be put into circuit, the other then being out of circuit. The return-circuit may be made by the ground, or preferably by the metallic conduit-pipe m , which is designed to extend along to or past 50 two or more points where power is to be applied, and a wire, 20, may connect this with the other battery-pole. The wires 1 2 lead each to one end of the coils D , and for the present purposes I will assume that the wires 55 3 4, which are connected with the other ends of the coils, lead to the ground or to the pipe m . The operator then closes circuit, say through wire 2, so as to excite the right-hand electro-magnet, draw down its armature, give 60 its rod e a thrust to the left, unseat the right-hand valve s , and allow pressure to escape from

the right-hand side of piston-head b' . The other valve s is then on its seat. The double-headed piston $b b'$ will then be shifted to the right by the conjoint action of the spring c^1 70 and the fluid-pressure which may have leaked past b by groove o or otherwise, and the spring c^2 will be compressed, the right-hand valve s will be forced to its seat as the piston approaches the end of its stroke, and will be held 75 to its seat, and the distributing-valve V will be shifted so as to uncover port a and open port a' to the exhaust, and fluid-pressure passing from chamber B will actuate the piston A' . Closing the opposite circuit through wire 1 80 will result by the same motions, but in a reverse direction, in reversing piston A' .

As another feature of improvement in connection with the present invention, I provide for closing other circuits by means of circuit-closers actuated by the main piston A' . To this end I add or attach to the latter a circuit-closing stem, A^3 , with a metallie ring, n , thereon, but insulated therefrom; and inside the case A^1 , in which it works, I arrange two pairs of contact-springs, 5 6, 7 and 8, in such manner that at or near the one end of the piston-stroke the ring n will come into electrical contact with one pair, 5 6, and at or near the end of the reverse stroke will make like contact 95 with the other pair. Each spring is in electrical connection with its own binding-post, and then by wires 9 and 10 one spring of each pair is electrically connected, one with the wire 1 and the other with the wire 2. Conducting-wires from the other springs of each pair may go to one or more signal-magnets, g , g' , &c., suitably arranged each to actuate its own signal h , h' , &c. For convenience of illustration I have represented three signals, each of 105 which may be of the style of Fig. 3, or of other known suitable style, form, or construction. The wire 11 leads through magnet g , and thence to ground or to conduit m . The wire 12 leads through magnets $g' g^2$ to the same return or ground. The signal h may be assumed to be a siding or junction signal, to be set at "safety" when and only when the switch is set to the siding, and $h' h^2$ to be main-line-signals, to be set to "safety" when and only when the main 115 track is unbroken.

Assuming still that wires 3 and 4 lead to conduit m , the electrical resistances of these wires should be somewhat greater than that of the added portions of the circuit through wires 9 and 11 or 10 and 12 and their connections. Then on the completion of the stroke of main piston- A' to the left (by which the switch is set to the siding) a further circuit will be through wire 1, (which is then in circuit,) wire 9, contacts 5 and 6, ring n , wire 11, through magnet g , and by conduit m back to the battery, so that signal h will be set to "safety."

The signals $h' h^2$, being on a broken circuit, 130 will be at "danger;" and it will be observed that this added portion of a circuit is not com-

pleted or closed into a closed circuit until the piston A' comes to or nearly to the end of its stroke, so that the signal h cannot be set to "safety" until the switch-rails have been 5 completely shifted, or so far shifted that a train may safely pass thereon.

The switch is reversed in the manner already described. As the piston A' nears the end of its motion or stroke to the right the ring n 10 makes contact with the springs 7 and 8, and so closes a circuit from wire 2 through wire 10, springs 7 8, and by wire 12 through signal-magnets g' g' back to ground or pipe m; hence as soon as the switch-rails are fully moved 15 over, and not till then, the current will be sent through 12, and the main-line signals h' h' will be shifted to "safety," but instead of connecting the wires 3 and 4 with pipe m', or carrying them to the ground, I prefer, in some instances, 20 to ground each through a make-and-break mechanism automatically operated by the piston motion. To this end I run the wire 3 to binding-post r, Figs. 1, 2, and the wire 4 to binding-post r', and these binding-posts are 25 electrically connected with contact-springs 13 and 14, such springs being so disposed that but one shall at any one time be in contact with a circuit-closing ring, z, on the stem A' and in electric connection therewith, so as 30 thereby and through the machine or by special wire to connect with the ground. This ring z is made on a sleeve, z'. The stem A', when moving to the right, carries the stem-sleeve z' along till its ring z makes contact 35 with spring 13, and then the motion of the sleeve is arrested by any suitable stop, as at w, and the motion of the sleeve in the other direction is arrested by a stop, w', as soon as the ring z makes contact with the spring 14. 40 Then, with the devices in the position shown in Fig. 1, the operator on shifting his key y', so as to put wire 2 in connection with the battery, will have a closed circuit by wire 2, right-hand magnet D, wire 4, binding-post r', spring 45 14, ring z, and thence to the ground, the other circuit through wire 1 being broken at the key'. This will shift the distributing-valve V, as already described, so as to admit fluid-pressure on the left-hand side of main piston A'. 50 As the work of this circuit is then performed, it may be broken, and this is done by moving the ring z away from the spring 14, and it is at the same time put in communication with the spring 13, so as to be ready for the making 55 of a circuit through wire 1; but the piston-stem A' continues its motion through the sleeve z' till the switch is fully shifted or properly set, and then the signaling-circuit is closed by the ring n and springs 7 and 8, and the signals are set, as already explained. Then, when 60 circuit is closed through wire 1, the current will pass through the left-hand magnet D by wire 3, binding-post r, spring 13, and ring z, through the machine to the ground. As soon as the 65 piston A' begins its motion this circuit is broken by the ring z leaving the spring 13 and

going to 14, and as the piston A' completes its stroke the corresponding signaling-circuit is closed by the ring n and springs 5 and 6, already explained; and it should be stated that 70 not only are the signals set to "safety" only at or after the movable switch-rails are brought to position, but also all conflicting signals are set to "danger" in advance of the switch motion, and this necessarily results from the 75 breaking of one circuit by the key y' preliminary to the making of another, since in such systems of apparatus the signals are by a weight, spring, or other device caused to go to "danger" on the breaking of the circuit, by 80 the closing of which they were previously set to "safety;" or, if the operator's key be otherwise arranged, the signaling-circuit will still be broken in advance of the switch motion, in consequence of the ring n moving away from 85 the contacts 5 and 6 or 7 and 8, by which the circuit was made, and this breaking of the circuit is done at or immediately after the beginning of the main piston stroke.

Changes of structure which do not materially change the operation or functions involved are included herein, as also all mechanical equivalents; and, further, I may state that I claim the benefit of the doctrine of mechanical equivalents, more particularly as regards those devices or mechanisms known in the arts as adapted to be used with substantially like function, in lieu of the magnets D or main piston A', or valve-moving piston b' b; also, I include herein the subject-matter of invention hereinafter claimed, even when applied to other purposes in the arts than those specifically named.

Believing myself to be the first inventor of an apparatus having a fluid-pressure piston 10 connected with the distributing-valve, in combination with an electrically-actuated valve or valves for governing or regulating the application of fluid-pressure to such piston, the same is accordingly claimed herein as within 110 the scope of the present invention, and without limiting myself to the form of piston or to the means of connecting it with the main or distributing valve, or to the form or construction of the electrically-actuated valve, 115 provided only that substantially the same mode of operation be preserved by a combination of devices, substantially as set forth; nor is it material that the electrically-actuated valves operate only to open escape-ports, as the function and operation would remain substantially 120 the same if the escape-ports were normally open and variations of fluid-pressure on the valve-moving piston were effectuated by the closing of one or the other by the use of an 125 electro-magnetic current.

In Fig. 4 I have illustrated the combination in series of the engines described, wherein the wires 11 and 12 of engine No. 1, instead of going out to constitute a signaling-circuit, go to 130 the opposite poles of the magnets of another like engine, No. 2. The wires 21 and 22 from

- the latter may go to another like engine in like manner, or may lead to signal-magnets g^3 g^4 , one or more, so as thereby to actuate signals h^3 h^4 , in the manner already described.
- 5 It will now be readily understood from this drawing and the previous description that the engine No. 1 may be used to shift one switch, the setting or shifting of which ought to precede the setting or shifting of some other 10 switch, which latter is to be shifted by No. 2. Then, as soon as the piston motion of No. 1 is complete and its switch has received its full throw, the circuit will be closed by one of the wires 11 or 12 to one or the other of the 15 magnets of engine No. 2, whereby, in the manner above described, another switch may be shifted and the circuit then be formed, by wires 21 or 22, through one or more signal-magnets to conduit m or to the ground. The 20 number of such engines thus electrically coupled up in series, so as to operate in succession from the same battery, may be increased at pleasure, as the work to be done may require, and the same is included as a 25 part of the present invention; but no claim is made herein relative to the combination of a signaling system or signal apparatus with the engines described, which subject-matter is reserved for separate applications.
- 30 I claim herein as my invention—
1. In combination with a fluid-pressure cylinder and piston, a valve governing the supply and exhaust, a piston to actuate said valve subject to fluid-pressure in opposite directions, escape-ports for alternately exhausting the pressure from one side or the other of such piston, and an electrically-actuated valve to each escape-port, substantially as set forth.
  2. In an electrically-actuated fluid-pressure 40 engine, a valve-moving piston arranged to be moved by fluid-pressure in opposite directions, in combination with a pair of electrically-actuated valves, each governing an escape-port, whereby on the opening of one 45 port or the other the piston will be caused to move accordingly, substantially as set forth.
  3. In combination with the main or distributing valve of a fluid-pressure motor, a piston connected therewith and operated in 50 one direction or the other by variations in a continuously-acting fluid-pressure, and an electrically-actuated valve governing the exhaust of fluid-pressure from one side of said piston, substantially as set forth.
  - 55 4. In combination with the main distributing valve of a fluid-pressure engine, and with a piston subject to a variable fluid-pressure in opposite directions to actuate the same, magnets D D and valves s s , for varying by electric agency the effective direction of the fluid-pressure on the piston, substantially as set forth.
  5. The combination of a cylinder or chest, B, provided with an inlet, a double-ended piston, b b' , and electrically-actuated valves s s , 65 governing outlets from said cylinder, as set forth.
  6. The combination of a cylinder or chest, B, having an inlet-port, b^2 , a double-ended piston, b b' , connected by a ported hollow 70 stem, c , and electrically-actuated valves s s , governing outlets from said cylinder, substantially as set forth.
  7. The combination of a cylinder or chest, B, provided with an inlet-port, a double-ended piston, b b' , connected by a hollow stem, c , rods c^2 c^3 , springs c^4 c^5 , and electrically-actuated valves s s , governing outlets from said cylinder, substantially as set forth.
  8. Electro-magnets D D, valves s s , arranged 80 at opposite ends of a fluid-pressure chamber, and a valve-moving piston working in said chamber, substantially as set forth.
  9. In combination with a magnet, D, and a valve, s , arranged to be unseated by the magnet when in circuit, and with a movable piston or piston-head, b' , a spring, c^6 , arranged between the piston or piston-head and a collar or stop on the valve-stem arranged to seat said valve, substantially as described. 85
  10. A stem, A^3 , taking its motion from the main piston A' of a fluid-pressure motor, and having an insulated conducting-ring, n , thereon, in combination with electrical contacts 5, 6, 7, and 8, substantially as set forth. 90
  11. A stem, A^2 , taking its motion from the main piston A' of a fluid-pressure motor, and having a conducting-ring, z , thereon, in combination with electrical contact-springs 13 and 14, arranged for contacts at different points of the stroke, substantially as set forth. 95
  12. Stems A^2 A^3 , taking their motion from the main piston A' of a fluid-pressure motor and carrying rings n z , in combination with contact-springs 5, 6, 7, 8, 13, and 14, substantially as set forth. 100
  13. In combination with a series of two or more electrically-actuated fluid-pressure engines, an electric circuit-conductor from one to another through the series, and an electric make-and-break mechanism on one arranged to be operated by or from the piston movement thereof, whereby to make or break the circuit to the next in the series with reference to the operation of such engines in succession, substantially as set forth. 105
- In testimony whereof I have hereunto set my hand.
